UNITED STATES PATENT OFFICE.

ROBERT V. CHEATHAM, OF LOUISVILLE, KENTUCKY, ASSIGNOR TO CHEATHAM ELECTRIC SWITCHING DEVICE COMPANY, OF LOUISVILLE, KENTUCKY, A CORPORATION OF KENTUCKY.

ELECTRICALLY-CONTROLLED RAILWAY-SWITCH.

SPECIFICATION forming part of Letters Patent No. 787,827, dated April 18, 1905.

Application filed August 9, 1904. Serial No. 220,137.

To all whom it may concern:

Be it known that I, ROBERT V. CHEATHAM, a citizen of the United States, residing at Louisville, in the county of Jefferson and State of Kentucky, have invented new and useful Improvements in Electrically - Controlled Railway - Switches, of which the following is a specification.

This invention relates to electrically - controlled railway-switches, the same being designed as an improvement upon the devices described and claimed in United States Patents Nos. 612,702 and 696,313, granted to me, respectively, October 18, 1898, and March 25, 1902.

The object of this invention is to simplify and otherwise improve the details of construction of the apparatus shown in the patents referred to, so as to render the same cheaper in construction and more efficient in operation.

Primarily the improvements relate to the circuit-changing and switch-tongue-throwing mechanisms.

The invention further aims to construct an electrically-controlled railway-switch-throwing mechanism which shall be comparatively simple in construction and arrangement, efficient in its use, strong, durable, and comparatively inexpensive to set up.

With the foregoing and other objects in view the invention consists in the novel combination and arrangement of parts hereinafter more specifically described, illustrated in the accompanying drawings, and particularly pointed out in the claims hereunto appended.

In describing the invention in detail reference is had to the accompanying drawings, wherein like reference characters denote corresponding parts throughout the several views, in which—

Figure 1 is a diagrammatic view illustrative of the invention. Fig. 2 is a sectional elevation of the circuit-changing mechanism; and Fig. 3 is a plan view, partly in section, of the switch-tongue-throwing mechanism.

Referring to the drawings by reference characters, 1 denotes the trolley-wire, which has a contact-block 2 secured thereto at points in ad-

vance of the railway - switch. The contact-block 2 is provided with contact-strips 3 4, arranged in parallel relation on the under side thereof and designed to be engaged by the trolley-wheel 5, carried by car. In connection with each contact-block 2 employed a circuit breaking and closing mechanism 6 and a switch-tongue-throwing mechanism 7 are employed. The circuit breaking and closing mechanism and the switch-tongue-throwing mechanism will be hereinafter referred to; but it will now be stated that the switch-tongue-throwing mechanism involves a double-solenoid magnet whose core is connected with the switch-tongue 9^a for operating the same in one direction or the other. The contact-block 2, the circuit breaking and closing mechanism 6, and the switch-tongue-throwing mechanism 7, are electrically connected in such manner so that when the trolley-wheel 5, carried by the car, moves in contact with the contact-strips 3 4 the wheel will act to bridge the circuit between the said strips, and the flow of the current will be caused to pass from the trolley-wire through the circuit breaking and closing mechanism 6 and thence to one or the other of the coils of the double solenoids of the switch-tongue-throwing mechanism 7, so as to move the core or armature of said solenoid and turn the switch-tongue 9^a in one direction or the other.

The electrical connections between the circuit breaking and closing mechanism 6, the contact-block 2, and the switch-tongue-throwing mechanism 7 will be hereinafter more fully referred to, as well as the travel of the circuits through the circuit breaking and closing mechanism to the switch-tongue-throwing mechanism.

The contact-block 2 is of the same construction as that shown in Patent No. 696,313, hereinbefore referred to, and as no claim is made therefor it is thought unnecessary to specifically describe the said contact-block 2.

The circuit breaking and closing mechanism 6 is preferably supported upon a pole on one side of the street adjacent to the contact-block 2 and is arranged within a suitable eas-

ing 9, which may be constructed of any suitable material and of any suitable shape, but preferably rectangular in contour.

The circuit breaking and closing mechanism 6 comprises a magnet 10, preferably in the form of a solenoid, and also a magnet 11, preferably in the form of a solenoid, and the said solenoids 10 and 11 are supported upon a shelf 12, fixedly secured within the casing 9. The solenoid 11 has its windings coarser than the windings of the solenoid 10. Consequently said solenoid 11 is of a lower resistance than the solenoid 10. The solenoid 10 is employed in connection with and is adapted to break what is termed the "main switch-throwing circuit" and the solenoid 11 employed in connection with and is adapted to close what is termed the "auxiliary switch-throwing circuit." The solenoid 10 is provided with a copper tube 13, which is non-magnetic, and vertically movable within said tube 13 is a solenoid-core 14, which is connected with or engages a vertically-movable shifting rod 15. Within the tube 13 is placed a body of mercury 18, the function of which will be hereinafter referred to. The core of the solenoid 11 is indicated by the reference character 19 and has connected thereto an upwardly-extending bar of fiber or other suitable material 20, and said bar of fiber 20 has attached to its upper end a link 21, the function of which will be hereinafter referred to. The shelf 12 immediately below the cores 14 and 19 is provided with recesses 22 to permit of a greater downward movement to said cores than if the recesses were not provided, the said recesses enabling a portion of the cores 14 and 19 to pass entirely through the solenoids. Within the casing 9, near the top thereof, is arranged a pivot-pin 22^a, and upon said pin 22^a is mounted one end of a lever 23 for breaking the main switch-throwing circuit, and said lever 23 is provided at its pivoted end with a downwardly-depending nose 24 and at its free end is provided with an opening 25 to provide for the passage of the shifting-rod 15. Arranged below the pivot-pin 22^a is an additional pivot-pin 25^a, upon which is mounted one end of the lever 26, which is adapted to close both the main and auxiliary switch-throwing circuits—that is to say, the lever 26 is so arranged with such respect to the lever 23 that when in contact with the nose 24 of the lever 23 the main switch-throwing circuit will be closed and when in contact with the contact-pin 27 the auxiliary switch-throwing circuit will be closed and the main switch-throwing circuit broken, as when said lever 26 contacts with the contact-pin 27 it is out of contact with the nose 24 of the lever 23. The lever 26 at its pivoted end is provided with a pair of protuberances 28 29, the protuberance 28 having the upper end of the link 21 attached thereto and the protuberance 29

carrying an adjustable weight 30, the function of which will be hereinafter referred to.

The solenoid 10 is always in series with a ground-solenoid, to be hereinafter referred to, of the switch-tongue-throwing mechanism, 70 said ground-solenoid just referred to being in what is termed the "main switch-throwing circuit." Said circuit the solenoid 10 is adapted to break when occasion requires. The solenoid 10 is only energized when the trolley-wheel connects the contact-strips 3 and 4 without a car taking power. The energizing of the solenoid 10 causes the core 14 to rise slowly through the column of mercury 18. This upward movement raises the weight 16, and should solenoid 10 be energized for a sufficient length of time the weight 16 and lever 23 will be raised high enough to release a lever 26, which breaks the main switch-throwing circuit through the solenoid 10. When this circuit 80 is broken, the core 14 sinks in the mercury by gravity to its original position through the medium of a weight 16. The latter and lever 23 are lifted high enough to release lever 26 only when the car is brought to a standstill with the trolley-wheel connecting strips 3 and 4. The ordinary passing of the trolley-wheel does not energize the solenoid 10 sufficiently long for the core 14 to be raised more than one-quarter of the distance required to 90 release the lever 26. When the trolley-wheel passes through the trolley-bracket and is at the same time taking power, the solenoid 11 is energized and the lever 26 is thrown over against contact-point 27, thereby throwing 100 the current into another solenoid, to be hereinafter referred to, of the switch-tongue-throwing mechanism and forms by such an operation what is termed the "auxiliary switch-tongue-throwing circuit." 30 is adapted to return the core 19 of the solenoid 11 to its normal position, as well as having a tendency to keep the lever 26 in contact with the nose 24 of the lever 23. The lever 23 carries a binding-post 31 for a wire 32, which leads 110 from said binding-post 31 to the solenoid 10.

The reference character 33 denotes a binding-post which is mounted upon the lever 26 and which receives one end of the leading-in wire 34, while the opposite end of said leading-in wire 34 is connected with the contact-strip 4.

The reference-characters 35 and 36 denote a pair of leading-in wires for the solenoid 11, and the wire 35 is connected with the contact-strip 3, and the wire 36 is connected with the trolley-wire 1. The solenoid 10 is connected with one of the solenoids of the switch-tongue-throwing mechanism 7 through the medium of the wire 37, and the other solenoid of the 120 switch-tongue-throwing mechanism 7 is connected with the contact-pin 27 through the medium of the wire 38. The main switch-tongue-throwing circuit comprises the leading-in wire 34, the lever 26, lever 23, wire 32, 130

and wire 37, and the auxiliary switch-tongue-throwing circuit comprises the wire 34, lever 26, contact-pin 27 and wire 38.

The switch-tongue-throwing mechanism is substantially the same as that shown in the Patent No. 696,313, with the exception that a bowed spring 39 is employed in lieu of the spring 74 of said patent and that the packing 53 and collar 55 of said Patent No. 639,313 is dispensed with and in lieu thereof a gasket 40 and brass nut 41 are employed. The double solenoid of the switch-tongue-throwing mechanism is indicated by the reference characters 42 43, and the core common to the said solenoids is indicated by the reference character 44. The solenoid 42 is connected with the wire 37, and the solenoid 43 is connected with the wire 38. It has been found that the bow-shaped or expansible spring 39 obtains a more satisfactory working than a straight coiled spring and that the employment of the gasket 40 and brass nut 41 insures a more satisfactory working than using a rubber packing-ring 53 and the metallic cap 55, as set forth in Patent No. 696,313.

As to the manner of the operation of that portion of the circuit breaking and closing mechanism which involves the solenoid having the copper tube and the mercury it will be stated that the current must pass through the solenoid 10 on its way to the ground-solenoid which operates the switch for the main track. The current passes through the solenoid 10 only when the car passes through the trolley-pan without any power on the car. When the car passes through the trolley-bracket without any power, the solenoid 10 is energized and the core therein begins to rise; but the car passes through the trolley-bracket so quickly that the core does not rise high enough to lift the nose 24 to release the lever 23. If it were not for the mercury in the copper tube 13, the core would lift the lever 23 instantly or, rather, move the nose 24 out of the path of the lever 26; but as it is the mercury must work its way past the core 14, which retards the upward movement of the core 14, so that the car has time to pass through the trolley-bracket before the nose 24 is raised high enough to release lever 26. After the car has passed through the trolley-bracket the core 14, through the intervention of the weight 16, sinks again in the mercury to its normal position at the bottom of the copper tube, and the nose 24 of the lever 23 also drops back to its normal position. Should the car stop with the trolley-wheel in the trolley-bracket and stand there for the space of four or five seconds, the core 14 will have time to rise high enough through the mercury to release the nose 24 from the lever 26. This would automatically cut the current off from the solenoid 10, and consequently the corresponding ground-solenoid or, rather, solenoid 43. Lever 26 is reset by the car starting again, for in starting the car the solenoid 11 opposite the solenoid 10 is energized sufficiently to throw lever 26 in position. When the car passes through the trolley-bracket and is at the same time taking power, lever 26 is thrown over against contact-pin 27, thereby throwing the current into the opposite ground-solenoid 42.

The operation of my improved apparatus is as follows: When it is desired to run the car along the main track, it is merely necessary for the motorman to cut off his motor when passing contact-block 2 and allow the momentum of the car to carry the same past said contact-block. Assuming the car to be approaching the switch, it will be observed that when the trolley-wheel 5 reaches the contact-block 2 the same will pass from the trolley-wire 1, due to the fact that said trolley-wire is deflected upwardly. The flanges of said trolley-wheel 85 will therefore be brought into contact with the contact-strips 3 and 4, bridging the circuit between the same. The current will then flow from the trolley-wire 1, through wire 36, solenoid 11, and wire 35, to contact-strip 3, 90 thence through trolley-wheel 5 to contact-strip 4, thence through wire 34 to lever 26, thence through lever 23 and wire 32 to solenoid 10, thence over wire 37 to solenoid 43, which energizes said solenoid 43 and will 95 draw the core 44 outwardly and move the switch-tongue 8 to the position shown in Fig. 1 of the drawings. It may be well to state that the current from trolley-wire 1 passing over wire 36 to solenoid 11 and then back to contact-strip 3 over wire 35 is too small to energize solenoid 11. Of course if the switch-tongue 9^a were already in the position just referred to there would be no action on the part of the solenoid 43 on the core 44, and consequently no movement of the switch-tongue 9^a would be effected. In other words, said switch-tongue 9^a would remain in the same position that it was in before. Assuming it to be turned to this position, however, 110 it is held in place through the action of the spring 39 and crank-arm 39^a of a lever 39^b, as switch-tongue 9^a is connected to the core 44 through the medium of the laterally-extending arm 39^c, link 39^d, lever 39^b, and link 115 39^e. In view of the manner in which the switch-tongue 9^a has now been set or retained in position it is evident that as the car approaches the switch it will pass along the main track thereof, as was intended. If it be 120 desired, on the other hand, to have the car move onto the branch track, the motorman leaves on the current through his motor when approaching the switch-block 2, and the operation of the device is as follows: When the trolley-wheel 5 reaches the fore end of the contact-strip 3, the circuit is closed through the wire 36 to the coil of the solenoid 11 and thence through the wire 35 to contact-strip 3. From the strip 3 the current is taken from 130

the trolley-wheel 5 down through the motor of the car and thence to ground. A heavy current is therefore drawn from the wire 1, which, passing through the solenoid 11, energizes the same sufficiently to raise core 19, thereby throwing the lever 26 against the contact-pin 27, and when the trolley-wheel reaches the fore end of the contact-strip 4 a portion of the current drawn from the trolley-wire 1 is shunted from the contact-strip 3 through the trolley-wheel 5 to the contact-strip 4 and thence through wire 34, lever 26, contact-pin 27, wire 38 to solenoid 42. With the flow of current through the solenoid 42 the same is energized and acts to withdraw the core 44 from the position it formerly occupied—that is, the same is drawn inwardly and swings the lever 39^b on its pivot, so as to move the switch-tongue 9^a from the position in which it is shown in Fig. 1 of the drawings to the position necessary to cause the car to travel from the main to the branch track. Said switch-tongue is held in this position after the solenoid 42 is deenergized by the action of the spring 39 on the crank 39^a of the lever 39^b. It will thus be seen that the operation of the device is automatic throughout. It is not necessary that the motorman or operator of the car know what the position of the switch is; but it is only necessary when it is desired to continue traveling along the main track to cut off the current to the car-motor when approaching the contact-block 2 and when it is desired to move from the main to the branch track to merely leave on the current to the car-motor when approaching the contact-block 2. When the solenoid 10 is energized, the mercury in the tube 13 retards the movement of the core 14 in such a manner as to prevent the disengagement of the nose of the lever 23 with the lever 26 in the manner as before stated, and as the passage of the trolley through the trolley-bracket is uninterrupted the energizing of the solenoid 10 is not of very long duration, for the reason that as soon as the trolley-wheel reaches the trolley-bracket the solenoid 10 becomes deenergized and the core resumes its normal position by gravity. This is evident owing to the employment of the weight 16.

The solenoids 42 and 43 and the switch-tongue-throwing mechanism have been shown as grounded through the means of the wires indicated by the reference characters 45 46. It is obvious that such solenoids may be grounded in any other suitable manner.

In regard to the adjustable weight 30, carried by the protuberance 39, it will be stated that said weight is removed in warm weather when the heaters are turned off the cars. When it is removed, it requires less current to energize the solenoid 11, which operates lever 26, so that in warm weather, when the weight 30 is dispensed with, the cars can operate lever 26 on the first contact-point of

their controller; but with the weight 30 attached to lever 26 the same cannot be operated unless the controller or rheostat is turned as far as the second or third point or to a point where the car would take more power than the 7c heaters and the switch-solenoids combined.

The mercury 18 in the solenoid 10 is what may be termed a "retarding" device for the core of said solenoid to prevent the breaking of the main switch-throwing circuit. The 7c employment of the mercury is shown to illustrate one form of a means to arrest the vertical movement of the core of the solenoid 10; but it is evident any other suitable means for this purpose can be employed, the mercury 8c being shown simply as one example for retarding the vertical movement in one direction of the core of the solenoid 10.

It is thought the many advantages of the electrically-controlled railway-switch constructed in accordance with the foregoing description can be readily understood, and it will furthermore be stated that changes, variations, and modifications can be resorted to without departing from the spirit of the invention or 9c sacrificing any of its advantages, and I therefore do not wish to restrict myself to the details of construction as shown in the accompanying drawings and described in the specification forming a part of this application, 9 but reserve the right to make such changes, variations, and modifications as come properly within the scope of the protection prayed.

Having thus fully described my invention, what I claim as new, and desire to secure by Letters Patent, is—

1. An electrically-controlled railway-switch comprising means for automatically closing a main switch-tongue-throwing circuit when power is shut off from the car and for breaking said circuit when the trolley carried by the car has its travel momentarily arrested in the trolley-bracket, and means for automatically closing an auxiliary switch-tongue-throwing circuit when power is supplied to the car.

2. An electrically-controlled railway-switch comprising means for automatically closing a main switch-tongue-throwing circuit when power is shut off from the car and for breaking said circuit when the travel of the trolley is momentarily arrested in the trolley-bracket, said means provided with a retarder to prevent breaking of the said circuit during the uninterrupted travel of the trolley through the trolley-bracket when power has been shut off from the car, and means for automatically closing an auxiliary switch-tongue-throwing circuit during the supply of power to the car.

3. An electrically-controlled railway-switch involving a switch-tongue-throwing mechanism comprising a pair of solenoids, a core common to both solenoids and connected with and adapted to shift the switch-tongue when either of said solenoids are energized, and a bow-shaped spring connected with said core

and adapted to retain the switch-tongue in its shifted position when the solenoids are deenergized.

4. An electrically-controlled railway-switch involving a circuit-changing mechanism, said mechanism comprising a pair of solenoids, one of which is provided with a retarder, a pair of levers adapted to contact with each other when one of said solenoids is deenergized and to be moved out of engagement with each other when the other of said solenoids is energized, and a contact-pin coöperating with one of said levers.

5. An electrically-controlled railway-switch involving a circuit-changing mechanism, said mechanism comprising a pair of solenoids, one of which is provided with a retarder, a pair of levers adapted to contact with each other when one of said solenoids is deenergized and to be moved out of engagement with each other when the other of said solenoids is energized, and a contact-pin coöperating with one of said levers, combined with a switch-tongue-throwing mechanism, a source of electrical energy, and suitable electrical connections between said source, lever, contact-pin, solenoids and switch-tongue-throwing mechanism.

6. An electrically-controlled railway-switch involving a circuit-changing mechanism interposed between a source of electrical energy and a switch-tongue-throwing mechanism, said circuit-changing mechanism comprising a pair of solenoids provided with movable cores, means carried by one of the solenoids for retarding the movement of its core, a pair of circuit making and breaking levers connected with said cores, a contact-pin coöperating with one of said levers, suitable electrical connections between the source of electrical energy and one of said levers, suitable electrical connections between the source of electrical energy and one of said solenoids, and suitable electrical connections between said contact-pin, the other of said solenoids, and said switch-tongue-throwing mechanism.

7. An electrically-controlled railway-switch involving a circuit-changing mechanism interposed between the source of electrical energy and the switch-tongue-throwing mechanism, said circuit-changing mechanism comprising a pair of solenoids, a movable core for each of said solenoids, a pair of circuit breaking and making levers adapted to contact with each other, means carried by the core of one of said solenoids for operating one of said levers when the solenoid is energized, and means carried by the core of the other of said solenoids for returning the other lever to its normal position after one of the levers has been operated.

8. An electrically-controlled railway-switch involving a circuit-changing mechanism interposed between the source of electrical energy and the switch-tongue-throwing mechanism,

said circuit-changing mechanism comprising a pair of solenoids, a movable core for each of said solenoids, a pair of circuit breaking and making levers adapted to contact with each other, means carried by the core of one of said solenoids for operating one of said levers when the solenoid is energized, means carried by the core of the other of said solenoids for returning the other lever to its normal position after one of the levers has been operated, and a contact-pin adapted to be engaged by the lever which has been operated by the core of the energized solenoid.

9. An electrically-controlled railway-switch involving a circuit-changing mechanism interposed between the source of electrical energy and the switch-tongue-throwing mechanism, said circuit-changing mechanism comprising a pair of solenoids, a movable core for each of said solenoids, a pair of circuit breaking and making levers adapted to contact with each other, means carried by the core of one of said solenoids for operating one of said levers when the solenoid is energized, means carried by the core of the other of said solenoids for returning the other lever to its normal position after one of the levers has been operated, and a contact-pin adapted to be engaged by the lever which has been operated by the core of the energized solenoid, combined with electrical connections between the source of electrical energy and one of said levers and one of said solenoids, electrical connections between the other of said levers and the other of said solenoids, electrical connections between said contact-pin and the switch-tongue-throwing mechanism, and electrical connections between one of the solenoids and the switch-tongue-throwing mechanism.

10. An electrically-controlled railway-switch involving a circuit-changing mechanism for closing main and auxiliary switch-tongue-throwing circuits, said mechanism comprising a pair of solenoids, one for the main and the other for the auxiliary switch-tongue-throwing circuit, means for energizing said solenoids when closing their respective circuits, and a retarder carried by the solenoid in the main circuit to prevent the breaking of the main circuit when the solenoid of the main circuit is momentarily energized.

11. An electrically-controlled railway-switch involving a circuit-changing mechanism for closing main and auxiliary switch-tongue-throwing circuits, said mechanism comprising a solenoid in the main circuit, a solenoid in the auxiliary circuit, a movable core for each of said solenoids, contact means operated by the core of the solenoid in the auxiliary circuit when the said solenoid is energized thereby opening the main circuit and closing the auxiliary circuit, and means arranged within the solenoid in the main circuit for retarding the movement of its core

when said solenoid is energized, thereby preventing the breaking of the main circuit.

12. An electrically - controlled railway-switch involving a circuit-changing mechanism for closing main and auxiliary switch-tongue-throwing circuits, said mechanism comprising a solenoid in the main circuit, a solenoid in the auxiliary circuit, a movable core for each of said solenoids, a lever connected with and actuated by the movable core of the solenoid in the auxiliary circuit when the solenoid is energized, a lever adapted to contact with the first-mentioned lever for closing the main circuit, means arranged in the solenoid in the main circuit for retarding the movement of the core thereof to prevent the disengagement of said levers and the opening of the main circuit when the solenoid in the main circuit is energized, and a contact-pin adapted to be engaged by the lever connected with the core of the solenoid in the auxiliary circuit when said solenoid is energized.

13. An electrically - controlled railway-switch involving a circuit-changing mechanism for closing main and auxiliary switch-tongue-throwing circuits, said mechanism comprising a solenoid in the main circuit, a solenoid in the auxiliary circuit, a movable core for each of said solenoids, a weighted lever connected with and actuated by the movable core of the solenoid in the auxiliary circuit when the solenoid is energized, a lever adapted to contact with the first-mentioned lever for closing the main circuit, means arranged in the solenoid in the main circuit for retarding the movement of the core thereof to prevent the disengagement of said levers and the opening of the main circuit when the solenoid in the main circuit is energized, and a contact-pin adapted to be engaged by the lever connected with the core of the solenoid in the auxiliary circuit when said solenoid is energized.

14. An electrically - controlled railway-switch comprising a double solenoid, a core common to both solenoids, suitable connections between said core and the switch-tongue, a solenoid, a movable core therefor, a lever connected to said core, suitable connections between said solenoid and the source of electrical energy, suitable connections between said lever and source of electrical energy, a solenoid, a movable core therefor, a retarder in said last-mentioned solenoid for the core

thereof, a contact-pin, suitable electrical connections between said contact-pin and said double solenoid, a lever having a nose adapted to contact with said first-mentioned lever, and suitable electrical connections between said lever provided with a nose and said solenoid provided with a retarder.

15. An electrically - controlled railway-switch involving a switch-tongue-throwing mechanism, said mechanism comprising means connected with the switch-tongue for shifting it, a gasket for forming a seal, a brass nut for securing said gasket in position, and a bow-shaped spring for retaining the switch-tongue in shifted position.

16. An electrically - controlled railway-switch involving a switch-tongue-throwing mechanism, said mechanism comprising means connected with the switch-tongue for shifting it, a gasket for forming a seal, a nut for securing said gasket in position, and a bow-shaped spring for retaining the switch-tongue in shifted position.

17. An electrically - controlled railway-switch involving a switch-tongue-throwing mechanism, said mechanism comprising a pair of solenoids suitably connected with an electrical source, a movable core common to both solenoids and connected with the switch-tongue for shifting it when the solenoids are energized, a gasket surrounding the solenoid, and adapted to form a sealing means, a brass nut for securing said gasket in position, and a bow-shaped spring for retaining the switch-tongue in its shifted position.

18. An electrically - controlled railway-switch involving a switch-tongue-throwing mechanism, said mechanism comprising a pair of solenoids suitably connected with an electrical source, a movable core common to both solenoids and connected with the switch-tongue for shifting it when the solenoids are energized, a gasket surrounding the solenoid and adapted to form a sealing means, a nut for securing said gasket in position, and a bow-shaped spring for retaining the switch-tongue in its shifted position.

In testimony whereof I have hereunto set my hand in presence of two subscribing witnesses.
